UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

SWITCH BOX.

Application filed October 6, 1920. Serial No. 415,053.

To all whom it may concern:

Be it known that I, HAROLD G. BAXTER, a citizen of Great Britain, and a resident of Baldwin, in the county of Nassau and State of New York, have invented a new and useful Improvement in Switch Boxes, of which the following is a specification.

My invention relates to switch boxes and particularly to the type of boxes used for enclosing entrance switches such as are employed in controlling lighting and power circuits.

An object of this invention is to provide a switch-box mechanism that is simple, durable and inexpensive to manufacture, wherein the movable cover for the box is provided with an auxiliary door closing an opening through which the fuses are accessible, and wherein the auxiliary or secondary door and the cover may be locked in closed position by a single locking element.

Another object is to provide a switch box having the above characteristics wherein the secondary door is so interlocked with the switch that opening movement thereof is prevented so long as the switch remains in closed position.

A further object is to provide a switch box of the character referred to wherein the auxiliary door and the switch are so interlocked that, when the switch is in open position, it cannot be closed so long as the door is in open position.

These and other objects, which will be made apparent throughout the further description of the invention, are attained by means of the switch box herein described and illustrated in the accompanying drawings, wherein:—

40 Figure 1 is a plan view of the switch-box mechanism showing the cover and the auxiliary door in closed position.

Fig. 2 is a longitudinal vertical section through the casing on the line II—II of Fig. 1, showing the enclosed switch mechanism in side elevation.

Fig. 3 is a transverse section through the casing on the line III—III of Fig. 1, showing the switch mechanism in end elevation.

60 Referring to the drawings, the apparatus includes a housing 4 having a bottom 5, end walls 6 and 7, and side walls 8 and 9. An insulating panel 10, which is mounted upon the bottom 5, supports two sets of stationary switch-jaw members 11 and 12, between

which a rotary switch shaft 13 is mounted upon bearings 14 and 15. This shaft carries the switch-blade member 16 for each pair of switch jaws 11 and 12 and is operated by means of a handle 17 secured to the shaft 18. The switch-operating mechanism A, which may be of any preferred type, so connects the shaft 18 with the switch shaft 13 that a predetermined angular movement of the handle 17 causes the switch shaft to rotate into or out of engagement with the switch-jaw members with a snap action.

As mechanisms for imparting a snap action to the switch shaft are old and well-known in the art, and as the mechanism herein illustrated forms no part of my invention, it is believed it is unnecessary to here describe in detail the operation of this device. It will be understood, however, that the switch action is such that, when the shaft 13 is turned substantially through 90° in a counter-clockwise direction, the switch members 16 are moved from their closed position, (shown in Fig. 2) to their open position (shown in dot-and-dash lines) and when the shaft is turned in a reversed direction a similar distance, the switch-blade members are moved to closed position. A cam 19 having an elevated surface 20 is mounted for rotation with the shaft 18 and serves to operate an interlocking mechanism to be hereinafter described.

The housing or casing 4 is provided with a hinged primary cover 21 which fits over the entire box structure and is hinged thereto by means of hinged members 23 that are secured to the side wall 9. The cover is provided with an opening 24 through which the fuse elements 25 which are mounted on the base 10, are accessible. This opening is closed by an auxiliary or secondary door 26 that is hinged to the primary cover 21 by means of the hinged members 27. A bolt latch serves to hold the door 26 in closed position with respect to the cover 21, which latch consists of a bolt housing 28 in which a sliding bolt 29 is free to slide longitudinally of the bolt housing.

This housing is secured to the cover 21 and permits the bolt to move into the opening 24 to a position beneath the door 26. The bolt socket 30 is secured to the under side of the door 26 and receives the projecting end of the bolt 29. When the bolt is moved into closed position within the

socket the auxiliary door cannot be opened. The bolt is provided with an operating pin 31; one end of which projects exteriorly of the cover through a slot 32, while the 5 opposite end projects interiorly of the casting through a slot in the bolt housing.

The cover 21 is provided near the edge opposite the hinged side thereof with a slot 33 which registers with a locking clip 34 10 that is secured to the side wall 8. When the cover is in closed position, the clip projects through the cover and the latter may be locked in closed position by means of a padlock 35 adapted to be inserted through 15 an eyelet 36 in the clip 34.

In order to lock the secondary door 26 in closed position by means of the lock 35, a bar 37 is slidably mounted on the cover 21 between the bolt housing 28 and 20 the underside of the cover. The bar is provided at one end with a wing so disposed that, when the bar is in the right hand position indicated at A in Figure 1, it occupies a position in the path of movement 25 of the pin 31 of the bolt 29 and prevents opening movement of the bolt. The opposite end of the bar 37 is provided with a wing 39 having an outwardly-bent ear 40 provided with a perforation 41 that 30 registers with the perforation or eyelet 36 in the clip 34 when the bar is in its extreme right-hand position.

It will be apparent from the foregoing, that when the perforations 41 and 36 are 35 aligned and the lock is passed through both eyelets, neither the cover nor the door can be opened.

Under certain conditions of installation, 40 it is not expedient to lock the auxiliary door 26 permanently, in which event it is necessary to provide means whereby the door 26 may be unlatched only when the switch is in open position. To accomplish this arrangement, a locking bar 42 that is 45 pivoted to the underside of the cover 21 by a pivot pin 43, is provided. One end of this bar is provided with a wing 44 that normally occupies the position in the path of movement of the bolt pin 31 when the 50 bar occupies the position illustrated in full lines in Fig. 2. The opposite end of the bar which is heavier than the end having the wing 44 is provided with a projection 55 that engages the cam 19 and, as shown in Fig. 2, engages the lower surface 46 thereof when the switch-blade member 16 is in closed position.

When the cam 19 is turned counter-clockwise through 90° by means of the shaft 60 18 and the switch is moved to open position, the elevated surface of the cam 19 engages the projection 45 and so turns the rocking bar 42 that the wing 44 thereof is moved out of the path of the bolt pin 31. The 65 position of the bar at such time is illustrated

in dot-and-dash lines in Fig. 2. It will be apparent from the foregoing that, when the switch is closed, the door 26 cannot be unlatched and when the switch is in open position the latch bolt 29 can be moved to 70 unlatched position to release the door.

In order to so interlock the door 26 with the switch that the switch cannot be closed so long as the door is open, the end of the 75 switch shaft 13 is provided with an arcuate extension 47 that rotates with the switch shaft. The underside of the cover is provided with an interlocked extension 48, so located with respect to the arcuate extension 47 that, when the cover is in open position, the extension 48 occupies a position in the path of movement of the arcuate extension, and, consequently, when the switch is open and the arcuate extension 80 85 90 95 98 99 100 105 110 115 120 125 130 135 140 145 150 155 160 - ing, a door therefor, a second door mounted on the other door, a switch and a fuse in the casing, a bolt latch for the second door having a projection extending into the interior 5 of the casing extending transversely of the bolt latch and a bar within the casing pivoted for movement across the path of the said projection whereby opening movement of the latch is prevented, and a cam member 10 movable with the switch for moving the bar across the path of the latch when the switch is moved to closed position.
4. A safety switch box comprising a casing, a door therefor, a second door mounted 15 on the other door, a switch and a fuse in the casing, a movable latch for the second door, means for locking the first door in closed position and means interlocking with the said means for holding the latch in closed 20 position.
5. A safety switch box comprising a casing, a door therefor, a second door mounted on the other door, a switch in one portion of the casing and a fuse in that portion of 25 the casing adjacent the second door, a movable latch for the second door, a locking eyelet mounted on the casing and projecting through the first door when the latter is in closed position adapted 30 to receive a locking element, for holding the first door closed, a bar slidably mounted on the underside of the first door and movable into the path of the movable latch

whereby opening movement of the latch is prevented, and having an eyelet registering with the eyelet mounted on the casing when the bar is in the path of the movable latch, 35 the said eyelet being adapted to be retained in registry with the eyelet mounted on the casing, by the said locking element.

6. A safety switch box comprising a casing, a door therefor, a second door mounted 40 on the other door, a switch in one portion of the casing and a fuse in that portion of the casing adjacent the second door, a movable latch for the second door carried by the first door, a locking eyelet mounted on the 45 casing and projecting through the first door when the latter is in closed position adapted to receive a locking element, for holding the first door closed, a bar slidably mounted on the underside of the first door and movable 50 into the path of the movable latch whereby opening movement of the latch is prevented and having an eyelet registering with the eyelet mounted on the casing when the bar is in the path of the movable latch, the said 55 eyelet being adapted to be retained in registry with the eyelet mounted on the casing, by the said locking element.

In testimony whereof, I have hereunto subscribed my name this 27th day of Sept., 60 1920.

HAROLD G. BAXTER.
